UNITED STATES PATENT OFFICE.

HORACE T. MANLOVE, OF EVANSTON, ILLINOIS.

LIFE-PRESERVER.

No. 797,136.

Specification of Letters Patent.

Patented Aug. 15, 1905.

Application filed April 24, 1905. Serial No. 257,237.

To all whom it may concern:

Be it known that I, HORACE T. MANLOVE, a citizen of the United States, residing at Evanston, in the county of Cook and State of Illinois, have invented certain new and useful Improvements in Life-Preservers; and I do declare the following to be a full, clear, and exact description of the invention, such as will enable others skilled in the art to which it appertains to make and use the same.

This invention relates to life-preservers; and one of the principal objects of the same is to provide means for automatically inflating a life-preserved sack or bag whenever the same is thrown into the water.

Another object is to provide a collapsible life-preserved sack with a casing which will hold the collapsed sack within a small space, but which will open automatically when the life-preserved has been thrown into the water or has been immersed at one end for a sufficient time to moisten the inflating medium.

These and other objects are attained by means of the construction illustrated in the accompanying drawings, in which—

Figure 1 is a central vertical sectional view taken through an inflating life-preserved made in accordance with my invention. Fig. 2 is a side elevation of a casing within which the life-preserved is adapted to be placed in order that it may occupy but a small space, and Fig. 3 is a cross-section on the line 2 2 in Fig. 2.

Referring to the drawings for a more particular description of my invention, the numeral 1 designates a collapsible india-rubber inflatable sack or bag, and 2 is a netting adapted to surround and inclose said sack 1 to prevent the same from being excessively inflated. Projecting into the mouth portion of the sack 1 is a tube 3, of metal or other suitable material, provided with an opening at one side thereof, said opening being covered by a suitable flap-valve 4 for a purpose which will presently appear.

Fitted within the outer end of the tube 3 is a plug 5, to which is secured a series of wires 6, said wires being contracted, as at 7, to support and hold a wick 8 in place. Above the contracted portions of the wires a carbide-compartment 9 is provided, and the upper ends of said wires are bent over the inflating medium 10, as at 11. It will be understood that any suitable medium, like calcium carbide, carbonate of soda, or other inflating medium or compound, may be used.

As shown in Figs. 2 and 3, a casing 12 is provided for inclosing the collapsed sack of the life-preserved. This casing may be provided with a curved side and a plain flat cover hinged at one edge on one side and provided with a series of fingers 13, said fingers being adapted to pass under the curled-over edge 14 of the casing to hold the casing closed. However, when water is permitted to pass into the tube and be conveyed, by means of the wick, into the inflating-chamber and the gas is generated therein to inflate the sack 1 the pressure of the sack will open the case by springing the fingers past the beaded edge of the case.

From the foregoing it will be obvious that my automatically-inflatable life-preserved may be readily carried within the pocket within a comparatively small case, such as I have shown, and that the life-preserved may be instantly inflated by dipping the end in water a sufficient time to fill the tube with water. The case is thus opened by the pressure of the inflated sack, when the device is ready for use.

The opening at the side of the tube and the valve 4 may be located in the plug 5 instead of in the tube 3. The casing 12 may be attached to the clothing by means of a clasp or safety-pin connected to the casing.

Various changes in the form, proportion, and the minor details of construction may be resorted to without departing from the principle or sacrificing any of the advantages of this invention.

Having thus described my invention, what I claim as new, and desire to secure by Letters Patent, is—

1. A life-preserved comprising a collapsible and inflatable sack, means for supporting an inflating medium within the sack, a wick leading to the inflating medium, and means for admitting water to the wick, substantially as described.

2. A life-preserved comprising a collapsible and inflatable sack, a tube extending into the same, a plug fitted to the tube, wire supports secured to the plug, a wick connected to said supports, an inflating medium secured to said wires, a valve in said tube and an inclosing case for said sack when the latter is deflated or collapsed, substantially as described.

3. A life-preserved comprising an inflatable sack, a netting surrounding said sack, a tube

extending into said sack, an inflating medium supported within said tube, a valve in said tube to admit water to the inflating medium, a casing for containing said sack, said casing having spring-fingers adapted to be disconnected when the sack is becoming inflated, substantially as described.

In testimony whereof I have hereunto set my hand in presence of two subscribing witnesses.

HORACE T. MANLOVE.
